THE NORRIS PETERS CO., WASHINGTON, D. C.

UNITED STATES PATENT OFFICE.

JOHN McTAMMANY, OF STAMFORD, CONNECTICUT.

MECHANICAL MUSICAL INSTRUMENT.

No. 908,798.

Specification of Letters Patent.

Patented Jan. 5, 1909.

Application filed March 4, 1907. Serial No. 360,402.

To all whom it may concern:

Be it known that I, JOHN McTAMMANY, of Stamford, in the county of Fairfield and State of Connecticut, have invented certain 5 new and useful Improvements in Mechanical Musical Instruments, of which the following is a specification.

This invention has relation to mechanical musical instruments, characterized by the 10 employment of a plurality of pickers for operating or causing the operation of the sounding devices, an actuator which effects the operation of the pickers, and a perforated selector which governs the operation of the 15 pickers, although, so far as certain features of the invention are concerned, they may be embodied in mechanical musical instruments of other types.

One of the objects of the present invention 20 is to provide an instrument in which the tone of the sounding devices is unmuffled, and to this end a novel arrangement is provided by locating the sounding devices and their pickers in front of the selector. In accordance 25 with this arrangement, the musical sheet is not interposed between the sounding devices and the auditor so as to muffle or suppress the tones, and the pickers may be exposed to view so that the auditor may observe the operation of the instrument.

Another object of the invention is to provide an instrument in which an endless selector of undeterminate total length may be employed so that the instrument may be 30 capable of reproducing as many times as may be desired, a composition of considerable length such as an overture or concerto. This is preferably accomplished in accordance with the present invention by 35 mounting the action upon a substantially upright support with a free space therebeneath, so that the selector may be accommodated and permitted to form into folds at the bottom of the space. To further accom- 40 plish this result, as well as to so dispose the action that the selector will be behind or in the rear of the pickers and the sounding devices, the pickers and the sounding devices are preferably mounted upon a hinged frame 45 or support which may be swung forward out of its active or operative position to permit the insertion or removal of the selector. Due to the fact that, in the particular embodiment of the invention which has been illus- 50 trated upon the drawings and which will be

subsequently described, the pickers, though governed by the selector, are actually operated by an actuator consisting of a grooved or fluted roll, I preferably journal the actuator in a pivoted support so that the endless selector may be placed upon the actuator. 60

In addition to the features thus briefly referred to, the invention includes others which will be described in detail and set forth in the claims.

Referring to the accompanying drawings,— Figure 1 represents in front elevation a complete instrument embodying the invention. Fig. 2 represents a section on the line 2—2 of Fig. 1. Fig. 3 represents an enlarged section 70 on the line 3—3 of Fig. 1. Fig. 4 represents a similar section with the hinged support swung upward and outward. Fig. 5 represents in front elevation one end of the picker shaft and the adjacent parts. Fig. 6 illustrates in 75 section the picker shaft and the pickers thereon. Fig. 7 illustrates several of the dampers. Fig. 8 illustrates in detail the actuator and its supporting frame. Fig. 9 represents a plan view of the same with the 80 actuator moved outward for the reception of a selector. Fig. 10 represents an end elevation of the means for rotating the actuator.

Referring to the drawings, an instrument is illustrated which is one embodiment of 85 the invention. The instrument consists of an upright case 20, which is paneled and ornamented as desired. The case is divided by a horizontal partition 21 into two main compartments. The upper compartment 90 is again divided by an upright transverse plate or partition 22 into an upper front compartment 23 and an upper rear compartment 24. The partition 22 constitutes the sounding board of the instrument. In the 95 compartment 23 is located the action and in the compartment 24 is located the motor from which power is transmitted to the operative portions of the instrument. The lower compartment is divided into three compartments by upright partitions 25, 25, which extend from the front to the rear of the 100 case. The middle compartment 26 serves to receive the selector which passes through an opening in the horizontal partition, 105 whereas the side compartments are horizontally divided by shelves 27, 27, to provide pigeon-holes 28 for the reception of the selectors or music sheets. The front of the 110 case is closed by a hinged door 30, which is

glazed so as to disclose to view the action and a portion of the selector. I have described the case in detail because, as will be explained, it is particularly adapted for the 5 mechanism which I utilize and forms a part of the present invention.

As previously indicated, I employ selectors which consist of elongated perforated sheets. These sheets, in accordance with my invention, are made of flexible material, preferably paper, and they are of any convenient length. While in accordance with the present invention, I preferably connect the ends of each selector so as to form, as it were, an 10 endless band, nevertheless the entire invention is not limited thereto. The advantage of employing a selector consisting of an endless band is that the selector may be perforated so as to effect the production of 15 a number of compositions so that the compositions may be given one after the other without the necessity of removing the selector this being often times a necessary feature 20 in a coin-controlled machine, in which the invention may be also embodied. On the drawings an endless selector is indicated 25 at 31.

Referring to Figs. 3 to 10 inclusive, 32 indicates a base plate which is attached to 30 the sounding board 22, as shown in Fig. 2, any suitable means being utilized for securing it in place. Said base plate is formed with a large aperture 33 immediately in the rear of the action. Said base plate is provided with two forwardly projecting ears or lugs 34, 34 between which is pivoted the end bar 35 of the frame having a cross bar 36 and a second end bar 37. Screw pins 38 pass through the ears or lugs 34 into the ends 40 of the end bar 35 and constitute pivots to permit the frame 36 to be swung about a vertical axis. The other end bar 37 is adapted to swing between ears or lugs 39, which, when the frame is in its active position, 45 support the free end thereof as illustrated in Fig. 8. This frame forms a support for what is termed the "actuator". This actuator consists of a grooved or slotted roll 40, the reduced ends of which are journaled in bearings 41, 41 on the end bars 35, 37 of the frame. Midway between its ends, the roll or actuator is provided with conical teeth or points 42 which are adapted to enter the lines of perforations α extending longitudinally of the selector midway between its side edges so that, when the grooved roll is rotated, the selector is fed thereby. By 55 swinging the frame forward, as shown in Fig. 9, the endless selector may be placed 60 upon the actuator with the teeth or points 42 registering with the apertures in the selector. It is to be observed that the upper edge of the cross bar 36 is beveled as shown in Figs. 3 and 4 so that the rear stretch of 65 the selector may not be impeded in its up-

ward movement toward the actuator. This cross bar, as shown in Fig. 3, also acts somewhat as a guide for the selector.

The base plate 32 is formed with forwardly projecting ears 43 (see Figs. 2 and 3) between which is hung a support 44. This support also has ears 45, and through the ears 43, 45, are passed screw pins 46 arranged horizontally so that the support 44 may be swung upward into position shown 75 in Fig. 4. Normally the support 44 hangs downward in front of the roll-carrying frame as shown in Fig. 3. The support is formed at its lower end with ears or lugs 47 for the reception of a locking bar or shaft 48. These 80 ears 47 are adapted to pass between ears or lugs 49 on the plate 32, said lugs 49 being provided with key-hole slots 50 open at their smaller ends. The ends of the bar 48, which project beyond the lugs 47, are flattened 85 so that they may pass into the smaller ends of the slots 50 and then be rotated so as to lock the support 44 against forward movement. On the projecting end of the bar or shaft 48, there is a milled head 51 by 90 which it may be rotated. The support 44 has a transverse slot 52 to receive the grooved actuator, and as shown in Fig. 3, the lower wall of the aperture is beveled or rounded to form a guide for the front 95 stretch of the selector. By means of the construction just described, the support may be moved forwardly so as to expose the selector and the actuator, and the actuator may be swung about its vertical axis or 100 pivot so as to permit the removal of the selector or the insertion of a different selector.

The pickers 53, of which there is a plurality, are supported upon what may be 105 termed a "picker shaft" 54. This shaft is journaled at its ends in bearings 55 on levers 56 mounted on horizontal pivots 57. Each of these levers is projected beyond its pivot as at 58, and between the projecting end and the support are springs 59, by which the picker shaft is held yieldingly toward the support. The pickers take the form of star-wheels; that is to say, each picker 60 comprises a hub having radiating fixed teeth 61 115 which are slightly beveled as shown. These pickers are strung upon the shaft 54 as illustrated in Fig. 6; that is to say, on the shaft is placed a disk 62 and on the disk is mounted a picker 60. Then there is placed upon 120 the shaft a washer or spacer disk 63, then another disk 62 and picker 60, then a washer 63, and so on. Pressure is then exerted axially upon the various members assembled on the shaft so as to bind them frictionally together, and suitable collars or sleeves, as at 65, are secured upon the shaft by any suitable means. It will be observed that the pickers are of less thickness than the disks 62 upon which they are mounted, so that, 130

while said pickers are free to rotate relatively to the washers and the disks, nevertheless when there is no opposition to their rotation, they will be rotated by their frictional engagement with said washers and disks. The shaft 54 is in such relation to the actuator 40, when the parts are in position shown in Fig. 3, that the tooth of a picker which registers with an aperture in the selector, may engage the teeth on the roll and be moved forward one step. By mounting the picker shaft in yielding bearings, the pickers are adapted to yield so as to prevent tearing of the paper. The paper follows a tortuous path about the actuator so as to intersect the path of movement of the teeth on the pickers. The shaft 54 is rotated by means to be described and one tooth on each of the pickers bears against the selector with a yielding pressure. As soon as a perforation registers with a tooth on one of the pickers, the picker begins to rotate, being frictionally impelled by the shaft and the friction washers thereon until said tooth enters between two teeth on the roll 40 and then the roll impels the picker one step of its revolution until the next tooth of the picker bears against an unperforated portion of the selector. In the event that the perforation in the sheet is elongated, the picker will be rotated step by step by the actuator or fluted roll until the tooth on the picker bears against an unperforated part of the selector, so as to produce what may be termed a "trill".

The particular tone - producing devices which I have illustrated comprise mechanical combs, indicated at 63 and 64. I have shown two combs but I may use more or less according to the volume of sound that is to be produced. These two combs are secured in any suitable way upon brackets 65, 66 attached to the support 44. There is one tongue on each comb for each picker, the pickers at a point intermediate or half way between the ends of the shaft 44 being omitted as otherwise they would engage the points or feeding teeth on the actuator.

The actuator and the picker shaft are actuated from a driving gear 67 (see Figs. 2, 3, and 50 10). Said gear intermeshes with and drives a pinion 68 on the reduced end of the actuator, as illustrated in Fig. 10, when the actuator is in its active or operative position. On the end of the picker shaft 54 is a larger pinion 69 which is adapted to intermesh with the pinion 68 when the support 44 is in its operative position.

The driving gear 67 is secured on a shaft 96 which latter has a bevel gear 95 engaging and 60 driven by a bevel gear 94 on an upright shaft 93 having a pinion driven by a gear 82 on the hub of a spring motor 79. Said spring motor is mounted on a base plate 70, and has a top disk 81 connected by pins 80 with the 65 gear 82. A suitable starting and stopping

device is operated by a shaft 88 having a handle 89.

To prevent the folds of the selector from falling outward when the door of the case is opened, I locate at the front of the middle 70 compartment upright rods 98, 98, as shown in Figs. 1 and 2. The dampers 99 are supported by a bar 100 carried by the support 44.

I do not herein claim broadly the combination with the selector which governs the action of the pickers, of the actuator which imparts movement to the pickers, and the pickers, as the same is claimed in co-pending application, Serial No. 96,381, filed March 3, 1902. 80

Having thus explained the nature of the invention and described a way of constructing and using the same, although without attempting to set forth all of the forms in which it may be made or all of the modes of 85 its use, I declare that what I claim is:—

1. In a mechanical musical instrument, an upright case, a horizontal partition therein, a vertical partition forming a sounding board and dividing the space above the horizontal 90 partition into a front compartment and a rear compartment, a motor arranged in the rear compartment, and an action located in the front compartment and supported upon said upright partition, the horizontal partition being formed with an opening for a selector sheet and the space below said partition being free to accommodate such sheet. 95

2. In a mechanical musical instrument, an upright case, a horizontal partition therein, a vertical partition forming a sounding board and dividing the space above the horizontal partition into a front compartment and a rear compartment, a motor arranged in the rear compartment, an action in the front 100 compartment and supported upon said vertical partition, upright partitions dividing said case below the horizontal partition into upright compartments, and shelves dividing the outer upright compartments into pigeon- 110 holes. 105

3. In a mechanical musical instrument, an upright case, a horizontal partition therein, a vertical partition forming a sounding board and dividing the space above the horizontal 115 partition into a front compartment and a rear compartment, a motor in the rear compartment, and an action in the front compartment, the space below the horizontal partition being adapted to receive the folds of 120 a flexible selector. 120

4. In a mechanical musical instrument, an upright support, sounding devices located in front of said support and supported thereon; and means for directing a selector from behind the support to position to control the sounding devices. 125

5. In a mechanical musical instrument, a base, a support hinged thereon, pickers mounted on said support, and a feeder for a 130

sheet located between the pickers and the base and adapted to be exposed when the support is moved about its hinge.

6. In a mechanical musical instrument, a base, a feed roll, a hinged support, a selector between the support and the feed roll, a picker shaft, pickers on the shaft, and yielding bearings for said shaft on said support.

7. In a mechanical musical instrument, a selector, a plurality of selector-governed pickers in front of the selector, and a support for the pickers movable to expose the selector.

8. In a mechanical musical instrument, a selector, a feed roll behind the operating portion of the selector, a plurality of selector-governed pickers in front of the selector, and a pivoted support for the pickers.

9. In a mechanical musical instrument, a selector, a displaceable feed roll therefor, a plurality of selector-governed pickers in front of the selector, and a movable support for the pickers.

10. In a mechanical musical instrument, a selector, a feed-roll therefor, a pivoted frame for the feed-roll, a displaceable support, and a plurality of selector-governed pickers on said support.

11. In a mechanical musical instrument, a pivoted actuator adapted to receive a selector consisting of a perforated band, in combination with a displaceable support, and pickers yieldingly mounted on said support.

12. In a mechanical musical instrument, a pivoted actuator adapted to receive a selector consisting of a perforated band, in combination with a pivoted support, a picker shaft yieldingly mounted on said sup-

port, pickers on said shaft, and sounding devices also mounted on said support.

13. In a mechanical musical instrument, an actuator having feeding teeth adapted to feed a perforated flexible band, in combination with a displaceable support, a plurality of selector-governed actuator-operated pickers, and means for yieldingly mounting said pickers on said support.

14. In a mechanical musical instrument, an upright base, an actuator pivoted at one end to said base to swing on a vertical axis, a support also pivoted to said base to swing away from said actuator, and pickers mounted on said support.

15. A mechanical musical instrument comprising a selector consisting of a flexible perforated band, a single feed and supporting roll for said band from which the selector depends, and an action controlled by the selector and actuated by said roll, in combination with a case inclosing said roll and said action and having a compartment to receive the depending portions of said selector.

16. A mechanical musical instrument comprising a driving gear, a feed-roll pivotally mounted at one end and having a gear on its other end adapted to engage the driving gear, and a displaceable picker shaft having a gear adapted to intermesh with the gear on the feeding roll.

In testimony whereof I have affixed my signature, in presence of two witnesses.

JOHN McTAMMANY.
